UNITED STATES PATENT OFFICE.

FRANK MESKER AND JACOB BEUC, OF ST. LOUIS, MISSOURI, ASSIGNORS TO MESKER BROTHERS IRON COMPANY, OF ST. LOUIS, MISSOURI, A CORPORATION OF MISSOURI.

METAL WINDOW CONSTRUCTION.

1,421,019.

Specification of Letters Patent. Patented June 27, 1922.

Original application filed May 13, 1920, Serial No. 381,043. Divided and this application filed February 23, 1921. Serial No. 447,118.

To all whom it may concern:

Be it known that we, FRANK MESKER and JACOB BEUC, citizens of the United States, residing at St. Louis, Missouri, have invented 5 ed a certain new and useful Improvement in Metal Window Constructions, of which the following is a full, clear, and exact description, such as will enable others skilled in the art to which it appertains to make 10 and use the same, reference being had to the accompanying drawings, forming part of this specification.

Our invention relates generally to metallic window construction and more particularly 15 to that type of metallic window having a stationary sash or frame and a swinging sash or frame which performs the functions of a ventilator, the principal objects of our invention being to provide a relatively 20 simple, strong, durable, and economical construction that is capable of being easily and cheaply produced and which, when properly closed, is weather and dust proof.

Our present application is a division of 25 an application filed by Frank Mesker, Clarence E. Smith and Jacob Beuc on May 13, 1920, Serial No. 381,043, and relates particularly to the construction forming the hingeless joint between the ventilator frame 30 and the window sash. By hingeless joint, we mean a joint in which there is not present a hinge pintle or trunnion such as is usually employed in constructions of this kind. We form a swinging joint between 35 the ventilator frame and the window sash, preferably by mutilating the inwardly extending flange of the T-shaped member of the window sash which forms one of the edges of the ventilator opening by notching 40 said flange and bending the tongue produced by the notching outwardly and downwardly to form a watershed. The outwardly extending flange of the ventilator frame member, which is preferably a commercially 45 rolled T-shaped structure, is likewise mutilated by forming a jog or bend therein which is designed to fit in the slot of the sash member, thereby forming a swinging joint, permitting the ventilator frame to swing on the 50 lower edge of the slot in the sash frame and also permitting the ventilator frame to be inserted or removed at will.

With the foregoing and other objects in

view, our invention consists in certain novel features of construction and arrangement of 55 parts, hereinafter more fully described and claimed, and illustrated in the accompanying drawings, in which—

Figure 1 is an elevational view of a metal window constructed in accordance with our 60 invention and looking at the outer side thereof.

Figure 2 is a vertical section taken approximately on the line 2—2 of Figure 1.

Figure 3 is an enlarged detail section 65 taken approximately on the line 3—3 of Figure 1 with parts broken away in order to more clearly illustrate the hinge connection between the swinging ventilator section and parts of the window sash. 70

Figure 4 is a perspective view of a portion 75 of one of the vertical rails of the window sash, the same being provided with a bearing for the swinging ventilator section.

Figure 5 is a perspective view of one of 80 the vertical rails of the swinging ventilator section.

Figures 6 to 9, inclusive, are detail side 85 elevational views of modified forms of swinging joints.

Figure 10 is a sectional view on line 10— 10 of Figure 6.

Figure 11 is a sectional view on line 11— 11 of Figure 6.

In the drawings, 1 indicates the upright 85 side rails of the sash, 2 the top rail, 3 the bottom rail, 4 the mullions or intermediate upright rails, and 5 the intermediate horizontally disposed rails. These rails are preferably constructed of commercially 90 rolled bars T-shaped in section with their centrally disposed webs outwardly presented.

The ventilator frame comprises a pair of 95 upright side rails 13, a top rail 14, a bottom rail 15, one or more upright intermediate rails or mullions such as 16, and one or more intermediate transverse rails such as 17.

The upright side rails 13 of the ventilator 100 frame are formed with a jog or bend 13^a near their centers so that the lower portions 13^b of said rails are offset with respect to the upper portions 13^c and this arrangement provides abrupt shoulders 13^a on the 105 flanges of said upright rails. (See Figure

5). To provide a bearing for these shoulders and to permit the ventilator frame to be mounted for swinging movement in the sash, the inwardly presented flanges 4^a of 5 certain of the intermediate upright members 4 are slotted horizontally and those portions of the flanges immediately above the slots are bent outwardly as designated by 4^b to form an overhanging dust or water- 10 shed.

When the ventilator frame is properly positioned in its opening in the sash, the shoulders 13^a on the upright side members 13 of the ventilator frame bear directly upon 15 the rounded upper ends 4^c of the inwardly presented flanges 4^a and thus the ends 4^c of said flanges constitute fulcrums or bearings upon which the ventilator frame is mounted for swinging movement.

20 Owing to the fact that the upper portions of the rails 13 are offset with respect to the lower portions, said upper portions will, when the ventilator is closed, lie immediately against the inner faces of the inwardly 25 presented flanges 4^a above the outwardly bent portions 4^b (see Figure 11), and the outwardly presented flanges of the lower portions 13^b of said side rails 13 will bear directly against the outer faces of those 30 portions of the flanges 4^a which are below the shoulder 4^c. (See Figures 1, 2, 3, 10 and 11). Also when the ventilator is closed, the top rail 14 will lie directly against the inner face of the depending flange of the intermediate 35 transverse rail 5 that is disposed above the ventilator opening, and the depending flange of the bottom rail 15 bears directly against the outer face of that portion of the transverse rail 5 that is disposed below the 40 ventilator opening.

In Figures 6 to 11, inclusive, we have shown different forms of means for maintaining the hinged connections between the ventilator frame and parts of the sash on which the 45 frame swings, and which arrangements are intended to counteract any tendency of the ventilator frame to become accidentally disengaged from its swinging position upon the sash frame.

50 In Figures 6, 10 and 11, the retaining means takes the form of one or more rivets 18^a which are inserted through the flanges of the upright rails 13 and the heads of the rivets projecting from the undersides of the 55 shoulders 18 so as to form depending lugs which retain said shoulders on the bearing 4^c.

The construction illustrated in Figure 7 includes a retaining lug or teat such as 18^b 60 that is formed in the underside of the shoulder 18 in any suitable manner, either by being soldered or brazed thereto.

In the construction illustrated in Figure 8 the metal in the rear portion of the shoulder 18 is distorted by being punched or

pressed downwardly to form a short shoulder or retaining flange 18^c, and in the construction illustrated in Figure 9, a tongue or finger 18^d is stamped or pressed from the web of rail 13 and bent upwardly against 70 the underside of shoulder 18. These retaining lugs or flanges are easily formed and are effective in holding the swinging frame in proper position upon the bearings 4^c, and particularly while the ventilator is swung 75 open to a considerable angle.

Our improved construction provides for the mounting of the swinging ventilator without the necessity of extraneous fittings such as hinges, brackets, and the like, and 80 the construction is such that the ventilator can be readily applied to the sash or removed therefrom and likewise it can be readily swung from closed to open position or vice versa. The members of the ventilator frame when closed fit snugly against 85 the adjacent parts of the sash and such an arrangement provides dust and weather-proof joints between the ventilator and sash frames.

90 Obviously minor changes in the details of construction may be made by those skilled in the art, without departing from the spirit of our invention, the scope of which is set forth in the appended claims.

95 We claim as our invention:

1. In metallic window construction, a sash 100 formed of metal rails and provided with an opening adapted to receive a swinging ventilator, the rails to the sides of the ventilator opening having inwardly presented flanges that are slotted to form horizontally disposed shoulders, and a ventilator frame positioned in the opening in said sash, said ventilator frame including flanged upright 105 side members, the flanges of which are bent intermediate their ends to provide shoulders which are adapted to rest upon and cooperate with the shoulders on the upright rails of the sash.

110 2. In metallic window construction, a sash formed of metal rails and provided with an opening adapted to receive a swinging ventilator, the rails to the sides of the ventilator opening having inwardly presented flanges that are slotted to form horizontally disposed shoulders, a ventilator frame positioned in the opening in said sash, said ventilator frame including flanged upright side members which are bent intermediate their 115 ends to provide shoulders which are adapted to rest upon and cooperate with the shoulders on the upright rails of the sash, that portion of the ventilator frame above the shoulders on the side rails thereof being offset with respect to that portion of the ventilator frame below said shoulders.

120 3. In metal window construction, a sash formed of metal rails and provided with an opening adapted to receive a swinging ven- 130

tilator, the rails to the sides of the ventilator opening having inwardly presented flanges that are slotted horizontally, and portions of the flange immediately above the slots being 5 bent outwardly, and a ventilator frame positioned in said opening and including numbers which are bent intermediate their ends to provide shoulders which bear upon the ends of the inwardly presented flanges of the 10 rails to the sides of the ventilator opening immediately below the slots therein.

4. In metal window construction, a sash formed of metal rails and provided with an opening adapted to receive a swinging ventilator, the rails to the sides of the ventilator opening having inwardly presented flanges that are slotted horizontally, portions of the flanges immediately above the slots being bent outwardly, a ventilator frame positioned 15 in said opening and having shoulders bearing upon the ends of the inwardly presented flanges of the rails to the sides of the ventilator opening immediately below the slots therein, and that portion of the ventilator frame above the shoulders on its side rails being offset with respect to that portion of said frame below said shoulders.

5. In metallic window construction, a sash formed of metal rails and provided with an 30 opening adapted to receive a swinging ventilator, the rails to the sides of the ventilator opening having inwardly presented flanges that are slotted to form horizontally disposed shoulders, a ventilator frame positioned 35 in the opening in said sash, said ventilator frame including upright side members which are bent intermediate their ends to form shoulders which are adapted to rest upon and cooperate with the shoulders on 40 the upright rails of the sash to the sides of the ventilator opening therein, and means on the undersides of the shoulders that are formed on the upright members of the venti-

lator frame for retaining said ventilator frame in swinging position upon the sash. 45

6. A metal window sash having a ventilator opening, an edge of which is formed by a flanged member, a swinging ventilator frame also having an edge formed of a flanged member, one of said members having 50 a slot in its flange and the other of said members having a jog or bend in its flange forming a shoulder for cooperating with one edge of said slot to form a pivotal axis for the swinging frame. 55

7. The combination of flanged members of a window sash forming a ventilator opening, the flanges of opposite members being presented inwardly and formed with slots, a swinging ventilator frame whose opposite 60 members are flanged; the flanges thereof being presented outwardly and overlapping said inwardly presented flanges, the outwardly presented flanges of said ventilator frame being bent to form shoulder portions 65 arranged within said slots.

8. The combination of vertically disposed flanged members of a window sash, the flanges of which are inwardly presented and lie in the same vertical plane, said flanges 70 being horizontally slotted, and a ventilator frame whose vertically disposed members have outwardly disposed flanges which are bent and offset so that the flanges will lie in different vertical planes above and below 75 said bent portions and on each side of the flanges of the sash members, said bent portions of the ventilator frame coinciding in location with the slots in the sash members.

In testimony whereof we hereunto affix 80 our signatures this sixteenth day of February, 1921.

FRANK MESKER.
JACOB BEUC.
